UNITED STATES PATENT OFFICE.

CHARLES DAVID MCCLINTOCK, DECEASED, BY RIO GRANDE VALLEY BANK & TRUST COMPANY, A CORPORATION OF TEXAS, OF EL PASO, TEXAS, ADMINISTRATOR, ASSIGNOR TO H. R. MCCLINTOCK, OF EL PASO, TEXAS, TRUSTEE, OF SIX-TENTHS FOR HIMSELF AND FOUR-TENTHS FOR MABEL BUCKINGHAM MCCLINTOCK AND ALDYTH MCCLINTOCK.

PROCESS OF VAPORIZING LIQUIDS.

1,363,136.

Specification of Letters Patent. Patented Dec. 21, 1920.

Original application filed December 7, 1916, Serial No. 135,689. Divided and this application filed September 5, 1918. Serial No. 252,706.

To all whom it may concern:

Be it known that the RIO GRANDE VALLEY BANK & TRUST COMPANY, a corporation of Texas, having its office in El Paso, Texas, 5 administrator of the estate of CHARLES DAVID MCCLINTOCK, deceased, who invented certain new and useful Improvements in Processes of Vaporizing Liquids, describes the invention by the following specification.

10 This application is a divisional application of an original application filed December 7th 1916, Ser. No. 135,689.

This invention relates to improvements in process of vaporizing liquids and refers 15 more particularly to a process of vaporizing a hydrocarbon liquid such as gasolene or kerosene, and then properly mixing it with air to form an explosive mixture.

Among the salient objects of the invention 20 are to provide a process in which the quantity of fuel and air can be definitely regulated, and the ratio of one to the other definitely determined; to provide a process in which a maximum efficiency of explosive 25 mixture can be obtained due to the independence and selective control of both the fuel and air supply; to provide a process in which more efficient and complete vaporization of the fuel is obtained, first, by causing 30 it to pass in finely divided veins to the mixing chamber, second by subjecting it to the action of a turbulent stream of air before it reaches the main body of air, and third, by preliminarily heating it as it passes to 35 said turbulent stream of air and before it reaches the main body of the air, whereby a homogeneous and dry mixture is obtained; to provide a process in which the feed of the fuel from the supply tank to the carburetor 40 is controlled directly by the power impulses of the engine and independent of any gravity of pressure feed or other extraneous or interposed devices; to provide a process of the character referred to.

45 In the present drawings we have shown the main views as applied to an internal combustion engine for use in motor cars and the like, although it is to be understood that in its broader aspects, the invention 50 is not limited to any particular or specific use.

In the drawings:

Figure 1 is a vertical sectional view of a carburetor constructed in accordance with our invention showing the vacuum fuel 55 valve partially open and the main air valve closed;

Fig. 2 is a rear end elevation of the construction shown in Fig. 1 with parts broken away and shown in section to bring out interior details of construction.

Fig. 3 is an enlarged detail sectional view of the capillary nozzle.

Fig. 4 is a side elevation showing the device as equipped for use in motor cars; 65

Figs. 5 and 6 are detail sectional views of a further modified construction in which the diaphragm is mechanically regulated by means of a cam or other suitable mechanism.

In the present invention the quantity of 70 air and fuel can be regulated absolutely independently of each other and the ratio of air to fuel and fuel to air can be definitely and positively determined. This fact should be constantly borne in mind in reading this 75 specification.

Referring now to the drawings—

1 designates a main body of the device having at its front side a flange 2, and closed at its rear end by a cover or closure plate 4. Between the plate 4 and the main body of the device is interposed a flexible diaphragm designated 3. This diaphragm fits against a seat 5, formed by a boss on the inner side of the closure plate 4. In a suitable aperture or recess of the main body of the device, is rotatively mounted a vacuum valve 6, manually controlled and operated by lever 7. Between the diaphragm and the rear wall of the main body portion is 80 formed a vacuum chamber 8, which communicates with the atmosphere through a small vent or duct 9, it being understood that this duct 9 merely tends to prevent a back vacuum into the vacuum chamber 8 85 when the valve 6 is closed and acts to keep the balance in the vacuum chamber at zero or atmospheric pressure. Between the rear face of the diaphragm and the inner wall of the closure plate 4, is formed the fuel chamber 10. This chamber 10 communicates as 90 shown clearly in Fig. 1, with capillary tubes 95 100

11, seated in a suitable recess in the plate 4 and the tubes 11 in turn connect to a transverse duct 12, leading to a capillary nozzle 13.

5 Gasolene can be delivered to the chamber 10 through the supply duct 14 (see Fig. 1) formed in the plate 4 or a heavier fuel such as kerosene can be delivered to the chamber 10 through duct 15. The supply of fuel through these ducts is controlled by a manually operated three-way valve 16, of well known construction. In each of the fuel ducts 14 and 15 is interposed a check valve 17 to prevent such fuel as may be above the valve from flowing back to the supply tank. Supply tanks (not shown) are connected to the ducts 14 and 15 respectively through fuel lines 18.

Describing now the main air valve control—In the lower end of the main body 1 is mounted a slideable air valve 19, having an operating stem 20 and valve spring 21. The port A is formed in the main body 1 and a similar port A—A is formed in the sliding valve 19. In the drawings, the valve is shown as closed. It can be opened to any desired degree by the distance the valve stem is raised. At its upper end, the body 1 is provided with an auxiliary air inlet B, which leads to any source of heated air supply, such for example, as air heated from the exhaust of the engine in the case of motor car construction. At its front side, the flange 2 has a discharge port D leading to the engine cylinders. C designates the vacuum air port leading to the front side of the diaphragm and controlled by the valve 6 heretofore described. The carbureter initially can be put into operation by means of the priming cylinder 22, (see Fig. 2) having a piston 23 and connecting stem or rod 24.

Referring again to the capillary nozzle 13, it has a tubular part 25 at its upper end and at its lower end longitudinally extending slots 26, cut in the nozzle in such a way as to divide the liquid fuel into a plurality of thin streams, or veins.

Before taking up the operation of the device, we will refer to the modified forms of construction shown in Figs. 5 and 6. Under certain conditions such as under slow moving engines, where heavy fuel is used it may be advisable to adopt a conical form of valve attached to the rear face of the diaphragm and moving with it. Such a construction is shown in Fig. 5, in which, to the diaphragm 8 is secured a conical valve 30, operated by the diaphragm and seating on the valve seat 5. As the construction is otherwise as heretofore described it need not be repeated in detail.

It may also prove advisable on large engines, requiring large quantities of fuel and close regulation for a constant supply of

fuel, to provide mechanical means for regulating the operation of the diaphragm. To this end a positive stop actuated by mechanical means and affording micrometric adjustment is provided. Such a construction is illustrated in Fig. 6. In this case, the valve 6 is dispensed with and the movement of the diaphragm is controlled by a cam shaft 27 having a cam 28 and a spring lever 29, which is directly acted upon by the cam and in turn impinges against the diaphragm. The rotative movement of the shaft 27 and cam 28 is accomplished through the medium of suitable leverage mechanism. Where this style of control is used, the vacuum air ports C are made of ample size but not governed in any way by the movement of the shaft but are allowed to remain open. The vacuum vent 9 is also not needed in this case. The action of the spring lever 29 is away from the diaphragm 3 so that the cam acts merely as an adjustable stop under the running condition as well as a positive closing device.

It will be apparent from the foregoing that if desired the fuel control valves and the air valves can be operated manually independently of each other. In certain cases, however, as for example, in motor cars, it is desirable to control the fuel and air together from a single lever or throttle. To this end in Fig. 4, I have shown one means of connecting these two valves but in which the option to shutting off the fuel entirely is retained with the means for selecting and maintaining any desired ratio of fuel to air. The degree of richness of the fuel charge is easily adjustable and without disturbing the air valve.

Referring to Fig. 4, the air valve stem 20 is provided with a bracket or arm 31 securely fastened to and slideable with the stem. Connected to this arm 31 by means of a short link 32 is a slide lever 33. The slot 34 of this lever is engaged by sliding pin 35 made fast to the lower end of the long link 36. The lower end of this long link is slideable in the slot 34 by means of a rod 37, which is operated by suitable means from some point within easy reach of the operator, as for example at the dash of the motor car. The long link 36 is connected at its upper end with the vacuum valve lever 7. It will be seen that any desired relative movement between the vacuum valve 6 and air valve 19 may be had by changing the position of the pin 35, or with the lower end of the long link 36 by means of the rod 37. It is apparent that if the pin 35 is placed at the point X (which is the hinge point in the slide lever 33) it will remain stationary and hold the vacuum valve 6 in its closed position, thus entirely shutting off the fuel while at the same time letting the air valve 19 be moved freely. Any ratio of movement may

be accomplished by moving the pin 35 from the point X toward the extreme position at Y. This position is shown by the dotted lines in Fig. 4, indicating that both the 5 vacuum valve 6 and air valve 19 are opened. The foregoing arrangement permits the air valves and fuel valves to be operated in unison but does not prevent ready and independent control of the fuel and air supply 10 or their ratio to each other.

It is to be noted that a diaphragm mounted in this way and having a seat on one side in its normal plane cannot have a fixed vibration period. Under the action of atmospheric pressure on the fuel side and intermittent periods of partial vacuum on the vacuum side, such partial vacuum being caused by action of the engine, the diaphragm will move away from its seat 5 to 15 return immediately; vibrating only once for each inspirating impulse. It is further to be noted that the vacuum produced by the action of the piston of a gas engine is nearly constant at normal speeds and that the vibratory movement of the diaphragm is controlled by the degree to which it is exposed to the vacuum. Closing the valve 6 entirely stops the movement of the diaphragm and no fuel is delivered to the fuel chamber as when 20 the diaphragm is seated on the seat 5, the capillary tubes are cut off from communication with the tubes 14 or 15. Opening the 25 vacuum valve 6 causes the diaphragm to move outwardly and away from its seat producing a similar vacuum in the fuel chamber 10. It will be understood that the vacuum which is thus produced in the fuel chamber cannot act to draw the fuel from the lines 11, 12 and 13, because that line is 30 affected by the same vacuum force going in the opposite direction or away from the fuel chamber.

The movement and quantity of fuel is regulated by the degree of movement of the 45 diaphragm, which is directly controlled by the vacuum valve 6. The effect of the vacuum in the fuel chamber 10, aided as it is by the second vacuum acting through the lines 11, 12 and 13 is to draw fuel from the fuel tanks through the ducts 14 and 15 to the valve 16, check valve 17 and fuel lines 18. In this way, the carbureter is supplied with fuel and regardless of where the supply tank may be located. The function of the small 50 check valves heretofore referred to is to prevent the liquid drawn into the fuel chamber 10, from returning to the fuel tank. In operation these small check valves 17 are assisted by the action of the capillaries which 55 of course possess the property of resisting the action of gravity to a considerable extent. They are still further assisted in action by the inertia of the liquid column, moving as it does practically continuously 60 in one direction. In addition, when the en-

gine is stopped the diaphragm resting on its seat 5 becomes an effective valve to aid the small check valves to perform their function.

No fuel will enter the fuel chamber except 70 through the vacuum action even if the fuel tank be placed considerably higher than the carbureter. This results from the fact that the diaphragm performs the function of a holding valve on the seat 5 due to its tension 75 when at rest and further due to the fact that the opening through the seat 5 is very small. This obviates the necessity of any float valves or similar devices.

The capillaries perform another function 80 than so far described. Besides possessing the property of sustaining a liquid against the action of gravity, they are able to generally steady the flow of liquid and prevent spouting, and the nozzle 13 has the still 85 other valuable feature of dividing the liquid into several small thin veins or streams, thus obtaining the maximum surfaces for exposure to the heated air. It will be noted that the nozzle 13 extends into the path of 90 the heated air current entering through the port B. The fuel may be said to run on the outside of this nozzle 13 instead of through it. This feature is important inasmuch as it is highly desirable to as thoroughly vaporize 95 the fuel as possible before it meets and is co-mingled with the main air current.

We have heretofore referred to the vent 9 which is provided to establish a zero pressure point (atmospheric pressure) from 100 which the vacuous condition may be gradually brought about by the opening of the vacuum valve 6. This action may be more fully understood if we start from that setting of the vacuum valve shown as closed 105 in Fig. 4, when the vent 9 is opened to the atmosphere and no communication is provided between the engine and the vacuum chamber; now if we open the vacuum valve a little the diaphragm is not affected because 110 the vent 9 is still large enough to maintain atmospheric pressure in the vacuum chamber. A further opening of the vacuum valve will overbalance this condition and the diaphragm will come under the influence 115 of the vacuous condition in whatever degree the vacuum valve may be opened. This arrangement affords a very flexible but positive beginning point from which to regulate the movement of the diaphragm and through it the quantity of the fuel charge. This vent 9 also prevents the retention of a partial vacuum in the vacuum chamber after 120 the valve 6 is closed.

The action produced by the diaphragm is 125 that of a positive pump with the capacity for minute adjustment of stroke. The small air port at B is fixed and will admit sufficient heated air to vaporize and draw the fuel and operate the engine at very light 130

loads or idling. The major portion of air needed to support the combustion is of course regulated by the valve 19. The valve itself is permitted a slight independent 5 movement to steady the velocity through the action of the spring 21. A feature of this air valve action is that it may be opened to its full capacity with the fuel shut off, thus allowing a free entry of pure air into 10 the cylinders, cooling and cleaning them and permitting the engines to turn over with great freedom.

In its broader aspects the invention is not limited to any details or steps in the process, except insofar as the same may be specifically limited in the appended claims.

We claim as our invention:

1. A process of producing a combustible mixture for internal combustion engines, 20 consisting in drawing fuel to a fuel chamber, positively controlling the amount of said fuel charge permitted to enter said fuel chamber by the vacuum action from the cylinders acting upon a fuel feed valve, causing 25 said fuel charges to pass in a finely divided condition into a heated turbulent air current, co-mingling such mixture with a regulated main air supply.

2. A process of producing a combustible mixture for internal combustion engines, 30 consisting in drawing fuel to a fuel chamber, positively controlling the amount of said fuel charge permitted to enter said fuel chamber by the vacuum action from the cylinders acting upon a fuel feed valve, causing 35 said fuel charges to pass in a finely divided condition into a heated turbulent air current, co-mingling said fuel with a main air supply and regulating the quantity of 40 main air and quantity of fuel independently of each other.

3. A process of producing a combustible mixture for internal combustion engines, 45 consisting in positively regulating the quantities of fuel drawn into the fuel chamber by controlling the vacuum action of the engine which mechanically governs the fuel intake, causing said fuel to pass in a finely divided condition into a heated air current, 50 co-mingling such mixture with a main air supply and finely delivering same to the engine cylinders.

4. A process of producing a combustible mixture for internal combustion engines 55 consisting in permitting positively regulated quantities of fuel to enter a fuel chamber, by concentrating the vacuum action from the cylinders upon a diaphragm valve, causing said fuel to pass in a finely divided condition into a heated turbulent air current, co-mingling said finely divided fuel particles with the main air supply and delivering the same to the engine cylinders.

5. A process of producing a combustible 65 mixture for internal combustion engines, consisting in mechanically controlling the fuel intake to the mixing chamber, permitting fuel to enter in regulated quantities only on the suction strokes of the engine 70 cylinders, causing said fuel to pass in a finely divided condition into a heated turbulent air current, co-mingling such mixture with a regulated main air supply.

6. A process of producing a combustible 75 mixture for internal combustion engines, consisting in directly drawing from the source of supply quantities of fuel into the fuel chamber, manually controlling at all times by separate and distinct means, the 80 quantities of fuel and air permitted to enter the mixing chamber, co-mingling the fuel and air in said mixing chamber and delivering the same to the engine cylinders.

7. A process of producing a combustible 85 mixture for internal combustion engines consisting in directly drawing fuel into a fuel chamber from the source of supply, manually regulating at all times by separate 90 controls the quantities of fuel and air permitted to enter a mixing chamber, causing said fuel to pass in finely divided condition into a heated turbulent air current on entering the mixing chamber, co-mingling such mixture with the regulated main air supply 95 and delivering the final mixture to the engine cylinders.
